CLAIM

The ornamental design for a canister filter, as shown and described.

DESCRIPTION

This application is related to U.S. patent application Ser. No. 12/410,436, filed Mar. 24, 2008, entitled “Canister Filter and Method of Fabricating the Same” by Lee Pendleton Morgan, which is herein incorporated by reference in its entirety.

FIG. 1 presents an isometric view of a canister filter of the present invention;

FIG. 2 is a front elevation view of the canister filter of FIG. 1;

FIG. 3 is a back elevation view of the canister filter of FIG. 1;

FIG. 4 is side elevation view of the canister filter of FIG. 1, the opposite side being a mirror image thereof;

FIG. 5 is a top plan view of the canister filter of FIG. 1; and, FIG. 6 is a bottom plan view of the canister filter of FIG. 1.

The broken lines depict portions of the filter cartridge that form no part of the claimed design.
